United States Patent Office

Des. 195,004
Patented Apr. 9, 1963

195,004

CONTAINER FOR DAIRY PRODUCTS OR THE LIKE

Clara Virginia Eicholtz, Midland, Mich., assignor to The Dow Chemical Company, Midland, Mich., a corporation of Delaware

Filed Nov. 17, 1961, Ser. No. 67,568

Term of patent 14 years

(Cl. D58—17)

Fig. 1

Fig. 4

FIGURE 1 is an elevational view of a container for dairy products or the like showing my new design;

The side of the container not shown is the same as the side shown.

I claim:

The ornamental design for a container for dairy products or the like, substantially as shown and described.
